UNITED STATES PATENT OFFICE.

ANDREW A. MEYER, OF BOSTON, MASSACHUSETTS.

AUTOMATIC WEIGHING-MACHINE.

SPECIFICATION forming part of Letters Patent No. 596,006, dated December 21, 1897.

Application filed April 28, 1897. Serial No. 634,224. (No model.)

To all whom it may concern:

Be it known that I, ANDREW A. MEYER, a citizen of the United States, and a resident of Boston, in the county of Suffolk and State of Massachusetts, have invented certain new and useful Improvements in Automatic Weighing-Machines, of which the following, taken in connection with the accompanying drawings, is a specification.

10 My invention relates to certain improvements in automatic weighing-machines.

The invention consists in the peculiar arrangement of levers for supporting the platform, in the means of transmitting motion from same to a shaft carrying a drum or cylinder having a series of numbers arranged spirally upon its periphery whereby said cylinder is moved and the weight indicated, and also in means for operating a shield (to dis- 20 close the weight) by a coin, as hereinafter set forth, and pointed out in the claims.

Referring to the accompanying drawings, Figure 1 represents a vertical longitudinal section of an automatic weighing-machine embodying my invention. Fig. 2 is a vertical transverse section of same. Fig. 3 is a horizontal section taken on line xx of Fig. 1. Figs. 4, 5, and 6 are respectively a side view, a plan, and an end view of the mechanism for operating the cylinder, and the coin-operating device for disclosing the weight.

A represents the base; B, the platform, which is formed with four lugs $b b' b' b'$ on its under side. To the lower end of the front lugs b are secured the outer ends of long levers C C', fulcrumed to lugs a on the side of the base A, and to the rear lugs b' are secured the ends of short levers C', fulcrumed to lugs a' on the side of the base A. The rear portion of these levers are bent in toward the center and come near together at their outer ends, upon which ends a bar D rests. The distance from the fulcrum of the long levers to their respective ends and the distance from the fulcrum of the short levers to their respective ends are proportionally the same, so that no matter on what part of the platform B the weight is placed the bar D will be raised as effectually as if the weight was placed in the center of the platform. Through the center of the bar D passes a rod E, the bar being secured thereto by a set-screw.

The rod E is guided at its lower end in a standard e and extends up for a short distance above a plate F', a strong spiral spring G being interposed between the bar D and plate F' by which the pressure on the ends of the levers C C' is regulated. To the upper end of the rod E is secured a collar f , in which is also secured the lower end of a rod E'. Said rod is bent to the rear and passes up through the casing F, that rests upon the base A.

The upper end of the rod E' passes through a lug H on the casing F, and a short distance below the lug a collar f' is adjustably secured to the rod. A light spiral spring G' is interposed between them. The object of the spring G is to hold the bar D down in its normal position, and that of the spring G' is for adjusting and preventing the rod E' being thrown up too suddenly. The upper end of the rod E' is formed with a rack E^2 , that is in gear with a pinion I, mounted upon a short shaft or spindle J, (see Figs. 4, 5, and 6,) carried by suitable bearings. Secured to or formed in one with the pinion I is a cog-wheel K, that is in gear with a pinion L, secured on a shaft M, carried in bearings N, and mounted upon this shaft is a drum or cylinder P, to which is secured a worm Q, the drum and worm being held on the shaft by a feather and groove, so that they will turn with the shaft, but be free to travel thereon. R is a finger secured to the plate S and fits into the thread of the worm, so that the latter will be fed forward or backward, according to the direction the shaft M is rotated.

The under side of the plate S is formed with a bracket s, to which the end of a lever T is fulcrumed, the outer end of which is held in a raised position by a spring t and is fitted with a plate t', upon which the coin falls. This lever is also formed with a small notch t^2 , that holds a lever U in the locked position. This lever U is fulcrumed to a standard at u, and a spring v draws the upper end away from the drum or cylinder P as soon as its lower end is released, and thus withdraws a shield U', secured to its upper end, and thus exposes the figures on the drum or cylinder P. To the bracket s is also fulcrumed a lever W, notched at its inner end and fitted with a pin w at its outer end and is held in position by a spring 2. X is a short rod chisel-pointed at

its lower end, which fits into the notch in the lever W and is normally held in the raised position. The upper portion of this rod X passes through the plate S, a pin x preventing it being forced beyond a certain distance. Upon the upper end of the rod X rests one end of a trigger Y, held thereon by a spring y. This trigger is fulcrumed to a standard on the plate S, and its inner end comes in contact with a series of pins k on the inner face of the wheel K, so that as the wheel K is rotated in one direction the pins k will depress the end of the trigger Y, but when rotated in the opposite direction one of the pins 15 will raise the end of the trigger, thus causing its other end to depress the rod X, and with it the inner end of the lever W, thus raising its outer end, when the pin w comes into contact with the lower end of the lever U and 20 forces the lower end of the lever in and throws its upper end outward, so that the shield U' will again cover the figures on the drum or cylinder P.

The operation is as follows: A weight being placed upon the platform B causes it to be pressed down, thus exerting pressure upon the outer ends of the levers C C' C' and causes their inner ends to be raised, thus lifting the bar D, and with it the rods E E'. The rack on 25 the upper end of the rod E' imparts motion to the pinion I and cog-wheel K, that transmits motion to the pinion L on shaft M, causing it to rotate, and with it the worm Q and drum or cylinder P, the finger R causing the 30 worm and drum to be fed along the shaft until the figures on the drum indicating the weight have been brought to the proper point. A coin now being inserted into the slot z falls upon the plate t' on the lever T, the weight 35 of the coin causing the outer end of the lever to be depressed, so that the lever U is released, which is by the spring v then thrown so that the shield U' will expose the figures on the drum or cylinder P. Upon the weight 40 being removed from the platform B the springs G G' force the rods E E' down, the rack E' on the upper end causing the pinion I, and with it the cog-wheel K, to be turned in the reverse direction, and said cog-wheel 45 turning the pinion L on shaft M brings the worm and drum back to their normal position. At the same time the pins k, coming into contact with the trigger Y, cause it to depress the rod X, which, acting upon the 50 lever W, causes the pin w to come into contact with the side of the lever U and force it back until its lower end enters the notch t' in the lever T, when the shield U' will again 55 cover the figures on the drum or cylinder P. 60 Thus the machine is reset ready for another operation.

Although I have shown and described the weighing-machine in connection with a coin-operating device for disclosing the weight, it 65 is obvious that the machine might be constructed for ordinary weighing purposes without said coin-operating device, in which case

a finger would be employed to point to the figures on the drum or cylinder.

What I claim is—

1. In a weighing-machine a pair of long levers and a pair of short levers, each connected at its outer end to lugs on the under side of the platform and a cross-bar resting upon their inner ends, each of said levers being fulcrumed to the sides of the base, the 70 distance from the fulcrum of the long levers to their respective ends and the distance from the fulcrum of the short levers to their respective ends being proportionately the same 75 substantially as set forth.

2. In a weighing-machine a pair of long levers and a pair of short levers, each connected at the outer ends to lugs on the under side of the platform, each of said levers 80 being fulcrumed to the sides of the base, the distance from the fulcrum of the long levers to their respective ends and the distance from the fulcrum of the short levers to their respective ends being proportionately the same, 85 whereby the inner ends of all the levers will be raised equally when the platform is depressed in combination with a cross-bar resting upon the inner ends of said levers and a rod passing through said bar for operating a 90 weight-indicating mechanism substantially as set forth.

3. In a weighing-machine a pair of long and a pair of short levers arranged as described in combination with a cross-bar resting upon their inner ends and a rod passing through said cross-bar, a rack on the upper end of said rod operating a pinion and mechanism for causing a drum or cylinder to rotate and indicate the weight substantially 100 as set forth.

4. In a weighing-machine a drum or cylinder having numbers indicating weights around its periphery and having a hub projecting on one side, a worm on the periphery 105 of said projecting portion, said cylinder being mounted upon a shaft so as to turn and slide thereon and gearing such as described for operating same when a weight is placed upon the platform as set forth.

5. In a weighing-machine a rod operated upon the depression of the platform, a rack on the upper end of said rod, a pinion in gear with said rack, a cog-wheel secured to said pinion, a shaft having a pinion secured thereon, a drum and worm mounted upon said shaft so as to rotate with but slide upon the same and a finger for causing the worm to travel along the shaft as it is rotated substantially as set forth.

6. In a coin-operating device a lever T, fulcrumed to a bracket s, and a spring t, for holding its outer end normally in a raised position, a lever U, fulcrumed at u, its lower end fitting into a notch t' in the lever T, a 130 lever W notched at its inner end, a bar X, resting in said notch, a pin w, in end of said lever W, and a trigger Y, the end of which is held in contact with the top of the 125

bar X, by a spring y, in combination with a wheel K, having a series of pins k, on its inner face and means for causing said wheel K, to be rotated first in one and then in the opposite direction substantially as set forth.

7. In a coin-operated weighing-machine a drum or cylinder P, having numbers spirally arranged upon its periphery, a worm attached thereto, means such as described for causing 10 the drum or cylinder to rotate with and slide upon the shaft in combination with a shield upon the end of a fulcrumed lever and means

for causing the shield to be withdrawn to disclose the weight and to again resume its normal position substantially as set forth. 15

In testimony whereof I have signed my name to this specification, in the presence of two subscribing witnesses, on this 1st day of March, A. D. 1897.

ANDREW A. MEYER.
